UNITED STATES PATENT OFFICE

1,963,817

GAS STOVE

Oscar Wiederhold, Skillman, N. J.

Application April 4, 1932, Serial No. 602,923

3 Claims. (Cl. 126—41)

The subject of my invention is a gas stove having therein a plurality of slabs of refractory material or so-called radiants which are treated with a chemical that will produce an abundance of 5 infra-red or heat rays as well as an abundance of visible or light rays which assist the penetrating power of the heat rays.

Another feature of my invention is that certain of the radiants are arranged at an angle to 10 each other or sloping with an opening between them while another radiant is mounted above this opening. The radiants are located adjacent the top of the stove so that the gases are baffled in their exit from the stove and all the smoke is 15 consumed.

Yet another feature of my invention is the fact that the Bunsen burners are located adjacent the radiants so that the flame comes in close contact with chemically treated radiants so that by catalytic 20 action all the carbon monoxide produced by the combustion of the gas is changed to carbon dioxide.

Still another feature of my invention is to provide air inlets adjacent the Bunsen burner mixing 25 chambers so that the secondary air for the flames is taken from the outside of the stove to cause complete combustion.

In general it is my purpose to provide a gas stove which shall be suitable for cooking by both 30 radiated and reflected heat and especially for broiling or toasting and is useful for preparing meat, such as steaks or chops, toasting bread, or cooking vegetables, such as roasting potatoes.

For a further exposition of my invention reference may be had to the annexed drawing and 35 specification at the end whereof my invention will be specifically pointed out and claimed.

In the drawing,

Figure 1 is a side elevation of my device with 40 parts broken away.

Figure 2 is a vertical cross section on line II—II of Figure 1 in the direction of the arrows.

In that embodiment of my invention selected for illustration in the drawing, my device is shown 45 as consisting of a shell generally indicated at 1 which may conveniently be formed of sheet metal and which may have at its lower forward face an opening 2. The opening 2 may be provided with a door if so desired. The stove may be open 50 at its top as indicated at 3 and may be provided with a grid 4 located in this opening.

At its upper end the stove is provided with a plurality of slabs 5 of refractory material known in the art as radiants. These slabs may be treated 55 with a chemical adapted to give off an abundance

of infra-red or heat rays as well as an abundance of visible or light rays when the slab is heated to incandescence. Examples of such a chemical are aluminum oxide, calcium oxide or thorium oxide. The chemical is applied to the radiant by 60 treating the radiant or a portion of it with a 50% solution of the chemical in water. I have shown in the drawing radiants having cones 6 which are the portions chemically treated but I do not however intend to be limited to radiants of this 65 description.

Beneath the slabs 5 but adjacent thereto are located the Bunsen burners for the gaseous fuel. These burners may conveniently consist of a mixing chamber 7 located within the stove so as to 70 be superheated. The mixing chambers 7 contain a plurality of jets 8 from which the gas escapes in flames. Beneath the jets 8 the mixing chambers may contain a wire netting or gauze 9. The Bunsen burner proper is indicated at 10 and is 75 shown as being of the double type which cannot become heated and which has given the best results in incandescent gas burners. A gas inlet pipe 11 is connected to the lower end of burner 10. In the side walls of stove 1 adjacent the 80 mixing chambers 7 I have provided a plurality of air inlet ports 12, as shown in Figure 1. There are also provided adjacent mixing chamber 7 and inlet ports 12 air baffles 13 which direct the secondary air which enters through the ports 12 8 directly to the burner flames issuing from jets 8. It is thus noted that the secondary air for the burner flames is drawn from outside the stove and not from inside so that complete combustion 85 of the gas is obtained. It will also be seen that 90 the Bunsen flames come into close contact with the chemically treated radiants so that the radiants, by their catalytic action, change all the carbon monoxide resulting from the combustion of the gas into carbon dioxide. Due to the location of the mixing chambers 7 and the inlet ports 12 the burner cannot light back nor will the 95 Bunsen flame leave the port openings.

In the lower part of my stove I may provide a plurality of shelves 14 adapted to support a 100 grid 15 or a pan 16 which are useful for cooking purposes.

It will be seen from the foregoing that when it is desired to cook on the stove the gas is turned on and ignited at the jets 8. The Bunsen flames 105 play upon the adjacent radiants heating them to incandescence regardless of the variation of gas pressure. As the radiants or deflectors are arranged on a slope or at an angle to each other there is a far better distribution of the heat 110

rays on the material to be cooked. Also, since the radiants are at an angle, as the heat rises, the radiants are brought to incandescence and are evenly heated throughout. There is provided a space between the sloping radiants and another radiant is provided opposite this space which also is heated to incandescence and serves to consume any smoke caused by the cooking. This smoke being composed of incompletely burned gas and of various vapors from the cooking contains carbon. When this carbon is consumed or comes in contact with the incandescent radiant it gives off ultra-violet light according to the well known principles of the carbon arc. This ultra-violet light is helpful in cooking thoroughly and quickly without burning or charring the food to be cooked.

The open top 3 of the stove may be utilized for pots or pans by placing them on the grid 4 where they may be used for cooking or may be kept warm.

I do not intend to be limited in the practice of my invention save as the scope of the prior art and of the attached claims may require.

25 I claim:

1. A gas stove including in combination a shell having an open top, a Bunsen burner having a plurality of mixing chambers within said shell beneath said open top, a pair of slabs of refractory material located between said mixing chambers and said open top and arranged at an angle to each other and with an opening between them, at least one of said slabs being

35

at an angle to a horizontal plane, another slab of refractory material above and confronting said opening, said shell having inlet ports therein in adjacent said mixing chambers for admitting secondary air, and baffles adjacent said ports and said mixing chambers. 80

2. A gas stove comprising, a shell having a substantially completely open cooking top, a pair of refractory slabs arranged at an upward opposite angle to each other with space between their upper ends for the escape of the products of combustion, and a Bunsen burner having a pair of gas outlet portions projecting into said shell closely adjacent the sides thereof, said gas outlet portions being located relative to said slabs so as to direct the flames issuing from said gas outlet portions upwardly along the surfaces of said slabs at an angle thereto. 85

3. A gas stove comprising, a shell having an open cooking top and a spaced oven compartment, a pair of refractory radiant slabs arranged at an upward opposite angle to each other and located above the oven compartment and having a space between said radiant slabs for the escape of the products of combustion, 100 a Bunsen tube having a pair of gas burner outlet portions projecting into said shell adjacent the sides thereof, and secondary air inlets located adjacent to said burner outlet portions, said burner outlet portions directing flames at 105 an angle to said radiant slabs. 90
